UNITED STATES PATENT OFFICE.

JOHN C. DAYNIX, OF PHILADELPHIA, PENNSYLVANIA.

PROJECTILE.

Application filed January 22, 1923. Serial No. 614,217.

To all whom it may concern:

Be it known that I, JOHN C. DAYNIX, a citizen of the United States, residing at Philadelphia, in the county of Philadelphia and State of Pennsylvania, have invented 5 certain new and useful Improvements in Projectiles, of which the following is a specification.

This invention relates to munitions of war 10 and more particularly to projectiles for use against aircraft of all types the primary object being to provide a projectile having associated means which will effect its explosion whether or not the "hit" be direct or 15 otherwise. In other words, I aim to provide an anti-aircraft projectile having means which will effect its explosion even though the nose of said projectile should not impact with or make a direct "hit"; or more 20 specifically defined, my novel projectile is devised for instantaneous explosion should it tangentially or glancingly pass in close juxtaposition to any part of an aeroplane, dirigible or analogous form of aircraft.

With the foregoing fundamental object 25 in view my invention essentially consists of a projectile having a series of inwardly foldable or collapsible arms about its longitudinal surface, said arms being adapted when 30 the projectile leaves a gun muzzle to automatically spring outwards in angular relation thereto while their free hooked ends are given a half turn for a purpose later on explained.

In the further disclosure of the invention 35 reference is to be had to the accompanying sheet of explanatory drawings constituting a part of this specification, and in which like characters of reference designate the 40 same or corresponding parts in all the views.

Figure 1 is a longitudinal section through 45 a projectile embodying one practical form of my invention with the collapsible arms indicated by full lines in the expanded or open position.

Figure 2 is a plan view of a detail member hereinafter more particularly referred to.

Figure 3 is a sectional detail plan taken 50 at the upper end of the explosive containing compartment; and

Figure 4 is a section on the line 4-4 in Figure 1.

According to my invention and as shown 55 in the drawings the numeral 1 designates

the shell of an anti-aircraft projectile, the same being tubular to provide an explosive containing compartment 2, a hollow nose compartment 3, and a rear end chamber 4 60 for a purpose later on explained. The forward end of the explosive containing compartment is closed in by an appropriate plug 5 while the rear end is separated from the chamber 4 by a plug 6. The explosive charge is designated by the numeral 7 and it may be of any suitable character, while the aforesaid plugs 5, 6 are axially connected by a longitudinal tube 8 that serves as a conduit for a purpose hereafter explained. 70 Longitudinal of the outer face of the aforesaid shell 1 are a plurality of diametrically opposed grooves or channels 9 in the forward ends whereof are transverse pins 10 that serve as hinge members for the forward tubular portions 11 of radially collapsible arms 12. Each of these radially collapsible arms 12 includes the aforesaid tubular portion 11, a second or rear tubular portion 13 securely connected thereto, and 80 an inner slightly telescopic rod 14 extending substantially the entire length of said arm. To the other end of the rod 14 there is attached a hooked claw 15 formed with a longitudinally extending integral latch 85 member 16 for a purpose later on explained. The rod 14 is adapted to be given a half turn in opposition to a compression spring 17 housed within the aforesaid tubular portion 11, said spring 17 having one end secured to a collar 18 and the other end abutting the forward end of the rear tubular part 13, and in order to provide for the aforesaid half turn movement, I secure 90 within the tubular portion 11 a sleeve 19 95 having an extended tongue portion 20 of slightly less than half its diameter, with which cooperates a pin 21 projecting radially from the rod 14. Thus it will be readily understood that when the hooked claws 15 are given a half turn or have their points inwardly directed—as when collapsing the arms 12—there will be exerted a torsional strain upon the springs 17. The forward end of each rod 14 is fitted with a contact shoe 22 and each said rod is adapted for a limited longitudinal movement as later on explained.

When collapsing the arms 12 into the aforesaid longitudinal grooves or channels 9 110 it is to be noted that the hooked claws 15 are given a half turn inwards so that they

can enter and be housed within the radially and longitudinally slotted parts 23 of the shell 1. In order to provide a retaining means for normally holding the arms 12 in collapsed position I fit the rear end of the shell 1 with a plug 24 having an axially central latch 25 under the action of a compression spring 26, and said latch 25 is formed with the integral cupped head 27 over which the hooked ends of the latch members 16 engage as will be readily understood on an examination of the drawing. Still further, it is to be seen that the outer end of the latch 25 is fitted with a head piece or nut 28 with which cooperates a radially disposed spring influenced latch 29 mounted within the aforementioned plug 24. Now it will be clearly apparent that when the charge at the back of the projectile is fired the force of its explosion will impel the latch 25 forward whereupon the radial latch 29 will be sprung at the back or outer end of the head piece or nut 28 thus freeing the collapsible arms 12 which will be automatically sprung outwards as hereafter explained.

Referring once again to the nose compartment 3, it will be seen that it is closed in at its outer end by an end piece 30 having a counter bore 31 in which is freely fitted a tube 32 having an enlarged end 33, said tube serving to house the firing pin 34 that is under the action of a compression spring 35 which normally tends to retain said pin 34 outwardly projected as shown. Externally concentric with aforesaid tube 32 is a second tube 36 which is screwed or otherwise secured at 37 into the nose compartment end piece 3' and said tube serves as a guide for the enlarged head 33 as well as housing an expansion spring 38. Integral with or fitted through the enlarged head 33 are a plurality of radially directed U-shaped members 39, the limbs 40 whereof are outward or forwardly directed relative to the longitudinal axis of the projectile.

Each of the hereinbefore described tubular portions 11 is fashioned with an integral and inwardly directed arm 41 having a toe 42 for cooperation with the enlarged head 33, and it will thus be readily seen that when the collapsible arms 12 are closed into the longitudinal grooves or channels 9 in the shell 1, the aforesaid toes 42 will force the enlarged head 33 and tube 32 outwardly in opposition to the spring 38. On the other hand when the collapsible arms 12 are released as hereinbefore set forth, the spring 38 will automatically force or rock the said arms 12 outwards through the cooperation of the enlarged head 33 with the toes 42 of the arms 41 as will be readily understood by those acquainted with the art.

To provide an automatic means for exploding the projectile when a direct "hit" is made, or when one of the collapsible arms

12 entangles or engages the object aimed at by one or more of its hooked claws 13, I employ a storage battery 43 that is housed within the rear chamber 4 said battery 43 being provided with a central binding post or terminal 44 and a plurality of outer binding posts or terminals 45 in number equal to the number of the collapsible arms 12. A conducting wire or wires 46 leads from the central binding post or terminal 44 through an insulation block 43' and the axially longitudinal tube 8 and its or their free ends are branched to provide leads 47, 48, the former of which is hooked over the free end of one of the limbs 40 of an U-shaped member 39 to provide a contact 49 while the latter is conducted into the aligning arm 41 to furnish a contact 50 in normal engagement with the contact shoe 22 on the inner end of the rod 14. A return wire 51 leads from each of the outer binding posts or terminals 45 through the tube 8, forward plug 5, into and through a fusible charge 52, thence into one of the arms 41 where it is terminated in a contact piece 53. Now it will be perfectly clear that in the event of a direct "hit" by the firing pin 34, a circuit will be closed through all of the fusible charges 52 by the engagement of the contacts 49, 50; and, similarly when one or more of the collapsible arms 12 are extended by the entanglement of its or their hooked claws 13 in the object aimed at or any part of an aircraft a like circuit will be closed by the engagement of the contact shoe 22 with the contact piece 53.

From the foregoing it will be readily seen that by my invention I have provided a very effective anti-aircraft projectile that will be found very effective in use. Furthermore, by locking the collapsible arms 12 as set forth, a safe and sane means is provided whereby a projectile of the type described cannot be carelessly exploded.

Obviously when the projectile is to be fired from a rifled gun, the collapsible arm claws 13 will be disposed at right angles relative to the longitudinal axis of said arms.

While there has been shown and described one practical embodiment of my invention it will be obvious that same is capable of varied modifications, therefore the right is hereby reserved to make such reasonable changes as fairly lie within the scope and intent of the subjoined claims.

Having described my invention what I claim as new and desire to secure by Letters Patent, is:

1. A projectile having a series of inwardly foldable arms about its outer surface, latching means for normally retaining said foldable arms housed in the wall of the projectile, said latching means being released by the firing charge to free the foldable arms,

and means operable by the firing pin or aforesaid foldable arms to effect the explosion of the projectile.

2. A projectile having a series of angularly expansible arms hingedly mounted at their forward ends in the body of the said projectile, hooked claws adapted for a half-turn at the rear ends of the expansible arms, latching means for engaging the hooked claws when inwardly turned for retaining the aforesaid expansible arms normally housed in the wall of the projectile, said latching means being released by the firing charge to free the expansible arms, and means operable by the firing pin or aforesaid expansible arm hooked claws to effect the explosion of the projectile.

3. A projectile having a series of opposed expansible arms hinged at their forward ends in the frontal part of said projectile, torsionally influenced telescopic hooked claws adapted for a half-turn at the rear ends of the expansible arms, latching means for engaging the hooked claws when inwardly turned for retaining the aforesaid expansible arms normally housed in corresponding grooves in the wall of the projectile, said latching means being released by the firing charge to free the expansible arms, and means operable by the firing pin or aforesaid expansible arm hooked claws to effect the explosion of the projectile.

4. A projectile having a series of diametrically opposed angularly expansible tubular arms hinged at their forward ends in the frontal part of said projectile, torsionally influenced telescopic rods adapted for a half-turn in said tubular arms and having hooked claws at their outer ends, spring influenced latching means for engaging with the hooked claws when inwardly turned for retaining the aforesaid expansible arms normally housed in longitudinal grooves in the wall of the projectile, said latching means being released by the firing charge to free the expansible tubular arms, and means operable by the firing pin or any one of the aforesaid tubular arm hooked claws for electrically effecting the explosion of the projectile.

5. A projectile having a series of diametrically opposed angularly expansible tubular arms hinged at their forward ends in the nose of said projectile, torsionally influenced telescopic rods adapted for a half-turn in said tubular arms and having hooked claws at their outer ends, latch members projecting from the back of said hooked claws, spring influenced retaining means for cooperation with the latch members for holding the aforesaid expansible arms normally seated in longitudinal grooves in the wall of the projectile, said retaining means being released by the firing charge, a spring in-

fluenced latch for holding the retaining means in its forward position to free the expansible tubular arms, and means operable by the firing pin or any one of the aforesaid tubular arm hooked claws for electrically effecting the explosion of the projectile.

6. A projectile having a series of diametrically opposed angularly expansible tubular arms hinged at their forward ends in the nose of said projectile, torsionally influenced telescopic rods adapted for a half-turn in said tubular arms and having hooked claws at their outer ends, latch members projecting from the back of said hooked claws, spring influenced retaining means for cooperation with the latch members for holding the aforesaid expansible arms normally seated in longitudinal grooves in the wall of the projectile, said retaining means being released by the firing charge, a spring influenced latch for holding the retaining means in its forward position to free the expansible tubular arms, a spring influenced firing pin in the nose of the projectile, having forwardly directed contact supporting members in line with the aforesaid tubular arms, heel portions at the hinged ends of the tubular arms for cooperation with the inner headed end of the firing pin to close an electric circuit from an enclosed storage battery through a fusible charge when a direct "hit" is made, and supplemental circuit closing means actuatable by any one of the aforesaid tubular arm hooked claws for also closing said electric circuit and thereby effecting the explosion of the projectile.

7. A projectile having a series of diametrically opposed angularly expansible tubular arms hinged at their forward ends in the nose of said projectile, torsionally influenced telescopic rods adapted for a half-turn in said tubular arms and having hooked claws at their outer ends, latch members projecting from the back of said hooked claws, spring influenced retaining means for cooperation with the latch members for holding the aforesaid expansible arms normally seated in longitudinal grooves in the wall of the projectile, said retaining means being released by the firing charge, a spring influenced latch for holding the retaining means in its forward position to free the expansible tubular arms, a spring influenced firing pin in the nose of the projectile having forwardly directed contact supporting members in line with the aforesaid tubular arms, heel portions at the hinged ends of the tubular arms for cooperation with the inner enlarged head of the firing pin and thereby closing an electric circuit from an enclosed storage battery through a fusible charge to explode the projectile when a direct "hit" is made, and supplemental contact members adapted to close said electric circuit whenever any one of the aforesaid

telescopic rod is extended by the engagement of its hooked claw in the object fired at.

8. In an anti-aircraft projectile, the combination with a source of electric energy and a circuit through charges fusible thereby, of a spring influenced firing pin, diametrically opposed angularly expansible tubular arms hinged at their forward ends in the nose of said projectile, torsionally influenced telescopic rods adapted for a half-turn in said tubular arms provided with hooked claws at their outer ends, said firing pin and telescopic rods when longitudinally moved effecting the closure of the electric circuit through the fusible charges to explode the projectile, and latching means for normally holding the aforesaid tubular arms collapsed into corresponding grooves in the projectile body.

9. In an anti-aircraft projectile including a source of electric energy, a circuit closable through charges fusible thereby, and a spring influenced firing pin for effecting the closure of said electric circuit when a direct "hit" is made, the combination of diametrically opposed angularly expansible tubular arms hinged at their forward ends in the nose of said projectile, torsionally influenced telescopic rods adapted for a half-turn fitted in said tubular arms and fashioned with claw shaped outer ends, said claw shaped outer ends having latch members extending therefrom, spring influenced means for normally holding the aforesaid tubular arms collapsed into the shell of the projectile by engagement with the latch members, and contact shoes at the inner ends of the telescopic rods for closing the aforesaid circuit when any one of said rods is extended by the engagement of its claw in the aircraft fired at.

10. In an anti-aircraft projectile including a source of electric energy, a circuit

closable through said source of electric energy and charges fusible thereby, and a spring influenced firing pin for effecting the closing of said circuit when a direct "hit" is made, the combination of diametrically opposed angularly expansible tubular arms hinged at their forward ends in the projectile nose, torsionally influenced telescopic rods fitted in said tubular arms and having claw-shaped outer ends provided with rearwardly projecting latch members, means for preventing said telescopic rods making more than a half-turn, a spring influenced locking member for cooperation with the latch members for normally holding the tubular arms and clawed ends collapsed into the shell of the projectile, a spring influenced member for preventing the recoil of the locking member when released, and contact shoes at the inner ends of the telescopic rods for closing the aforesaid circuit when any one of the telescopic rods is extended by the engagement of its claw in the aircraft fired at.

11. In an anti-aircraft projectile including a source of electric energy, a circuit closable through said source of electric energy and a charge fusible thereby, and diametrically opposed angularly expansible telescopic arms adapted to close said circuit whenever the free hooked end of any one of said arms engages with the aircraft fired at, the combination of a firing pin including concentric tubular members, reversely stressed springs interposed between the firing pin and said tubular members, and forwardly directed contact members carried by the firing pin to effect the closure of the aforesaid electric circuit when a direct "hit" is made.

In testimony whereof I affix my signature this 19th day of January, 1923.

JOHN C. DAYNIX.
